UNITED STATES PATENT OFFICE.

TAROKICHI KURODA, OF LOS ANGELES, CALIFORNIA.

SOAP LEAF.

Application filed December 27, 1927. Serial No. 242,675.

This invention relates to improvements in soap leaves, and its objects are to provide a cleaning medium in the form of a pad, and to provide a pad of this character which is neat and sanitary, and which may be carried in the pocket.

Another object is to provide a soap of this character, which has qualities that prevent sticking to the hands, and which will lather freely and quickly.

To attain these advantages, I provide a soap leaf, having a base of paper and having a series of perforations.

In the drawings, Figure 1 is a plan view 15 of a single soap leaf. Fig. 2 is a fragmentary sectional view of a soap leaf enlarged. Fig. 3 is a perspective view of a pad of the soap leaves.

Referring to the drawings, the pad 11 has 20 cover elements 12, of paper, and consists of a number of soap leaves 13. Each soap leaf consists of a base 14, of thin paper, and coated on both sides with a thin layer 15, of soap. The leaves each have a series of perforations 25 16. These perforations serve to prevent the sticking of the leaf to the hands when used. They further cause the soap to lather more quickly, and the paper material serves as a 30 mild abrasive in connection with the detergent materials. The abrasive effect is at-

tained by employing a paper fabric that disintegrates under vigorous rubbing with the hands. The soap leaves are very thin and therefore a number of them will form a thin pad as shown. Their efficiency is increased 35 by providing the perforations in each leaf.

From the foregoing description and drawings, it may be seen that I have provided an efficient form of soap leaves, which may be carried in a sanitary manner in the pocket. 40

I claim:

1. A soap leaf, consisting of a base element of thin paper, and a coating of soap material on each side of the paper, the leaf having a 45 series of perforations therein, and said paper fabric being disintegrable under vigorous rubbing.

2. A soap leaf, comprising a base element of thin paper disposed between two layers of soap material, and perforations in the leaf 50 formed thereby.

3. A soap leaf having two layers of soap material, and a disintegrable paper fabric element disposed between the soap material 55 layers, and having a series of perforations therein.

In testimony whereof, I hereunto affix my signature.

TAROKICHI KURODA.
